UNITED STATES PATENT OFFICE.

JOHN S. MAXWELL, OF RICHMOND, INDIANA.

DESIGN FOR A BALLOON-VALVE.

55,135.

Specification for Design.

Patented May 11, 1920.

Application filed December 20, 1918. Serial No. 267,737. Term of patent 14 years.

To all whom it may concern:

Be it known that I, JOHN S. MAXWELL, a citizen of the United States, residing at Richmond, county of Wayne, and State of Indiana, have invented a new, original, and ornamental Design for a Balloon-Valve, of which the following is a specification, reference being had to the accompanying drawing, forming a part thereof.

Figure 1 represents a perspective view of the inner side and Fig. 2 a perspective view of the outer side showing my design.

What I claim as new and desire to secure by Letters Patent, is:

The ornamental design for a balloon valve, substantially as shown.

JOHN S. MAXWELL.
